US0D1019338S

(12) **United States Design Patent** (10) **Patent No.:** **US D1,019,338 S**
(45) **Date of Patent:** **** Mar. 26, 2024**

(54) **LATCH PIN**

(71) Applicant: **Guangzhou Mibo Zhilian Technology Co. LTD**, Guangzhou (CN)

(72) Inventors: **Zeping Yang**, Jingzhou (CN); **Ziyi Long**, Beijing (CN)

(73) Assignee: **Guangzhou Mibo Zhilian Technology Co. LTD**

(**) Term: **15 Years**

(21) Appl. No.: **29/899,818**

(22) Filed: **Aug. 14, 2023**

(30) **Foreign Application Priority Data**

Jul. 13, 2023 (CN) 202330439703.4

(51) **LOC (14) Cl.** **08-07**

(52) **U.S. Cl.**

USPC **D8/343**

(57) **CLAIM**

The ornamental design for a latch pin, as shown and described.

DESCRIPTION

FIG. 1 is a top perspective view of a latch pin showing our new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is the perspective view of the latch pin in an environment of use.

Broken lines in the drawings depict portions of the environment of use of the latch pin that form no part of the claimed design.

1 Claim, 9 Drawing Sheets
